UNITED STATES PATENT OFFICE.

VINTON E. SISSON, OF CHICAGO, ILLINOIS, ASSIGNOR TO WALTER P. MURPHY, OF
CHICAGO, ILLINOIS.

CAR END FRAMING.

1,080,725.

Specification of Letters Patent.

Patented Dec. 9, 1913.

Application filed August 31, 1911. Serial No. 647,000.

To all whom it may concern:

Be it known that I, VINTON E. SISSON, a citizen of the United States, and a resident of the city of Chicago, in the county of Cook and State of Illinois, have invented a new and useful Improvement in Car End Framing, of which the following is a specification.

My invention relates to the end framing of railway cars, and particularly to the arrangement of end posts, end sill, draft girders, and striking-casting, or buffer to form a simple and strong structure to resist the heavy shocks which these parts have to sustain in service.

My invention further relates to the manner of supporting the draw-bar carry-iron so as to relieve it of undue strain and wear from the constant movement of the draw-bar, and to transmit directly to the car framing any shock coming upon this member due to longitudinal movement of the draw-bar, at the same time leaving it free to accommodate itself to the lateral position of the draw-bar.

My invention further relates to the details of construction of car end framing and buffers as more fully appear in the embodiment of my invention illustrated in the accompanying drawings and more particularly pointed out in the claims.

No claim is made herein to the centering device for the draw-bar except in so far as the striking casting is modified to coöperate with said centering device. The draw-bar centering device is described and claimed in applications Serial Nos. 646998 and 646999, pending concurrently herewith.

In the drawings, in which like characters are used to designate like parts wherever they occur,—Figure 1 is a view of a portion of the end framing for a car showing the striking-casting and draw-bar carry-iron in elevation; Fig. 2 is a part top plan of the same, partly in section on the line 2—2 of Fig. 1; Fig. 3 is a vertical section through the sill showing the striking-casting in end elevation and a portion of the draft girder in side elevation; and Fig. 4 is a vertical section on the line 4—4 of Fig. 1, showing a portion of a draft girder and end posts.

Referring to the drawings, there is illustrated a portion of the end of a car showing the end sill 1 bridging the ends of the longitudinal side sills (not shown) and draft

girders 3, and riveted to the latter. The end sill projects above the ends of the draft girders, and an angle 2 is positioned adjacent the top flange of the sill on its back face with one leg resting on the draft girders, and riveted to both and to the striking-casting 4. The lower ends of the end posts 15 rest upon the horizontal web of the angle, and are secured to the end sill by rivets passing through the flange, angle, end sill and striking-casting, as shown in Figs. 3 and 4. The draft girders are deeper than the end sill, and are notched out at 5 to take the end sill, and also provided with flanges 6 and 7 on their ends to which are riveted the end sill and striking-casting, respectively.

The striking-casting 4 is formed with a flange 8 fitting the end sill and riveted thereto, some of the rivets going through the flanges 6 of the draft girders and some serving to secure the lower ends of the end posts as well. A projection 9 is formed on the striking-casting to back up the draw-bar head and to take any shocks of collision. This projection or bumper is slightly convex in plan, the radius of curvature of the outer surface being the approximate distance to the point at which the draw-bar is pivoted to the car, so that for all positions of the draw-bar there will be the same distance between the rear side of the draw-bar head striking horn and the adjacent portion of the striking-casting. On both sides of this portion 9 there extend hollow arms 10 which are recessed in their top faces and bifurcated to provide bearings for the trunnions 11 of links 12. These links are embraced between the front and rear walls of the arms 10, and are pivotally connected to the draw-bar carry-iron 13 to support the latter. The arms 10 project downward on both sides of the draw-bar and the lower edges next the draw-bar are notched at 14 to form guides for the ends of the carry-iron. By this arrangement the draw-bar and carry-iron can swing laterally on the links, but any thrust on the carry-iron along the axis of the car will be resisted by the notched lower edges of the hollow arms, thus relieving the links of buffing shocks. The rear walls of these arms 10 are directly riveted to the ends of the draft girders, so as to form a very rigid support for the endurance of shocks coming on these arms. The front walls of these arms 10 serve as a

protection to the links as well as assist in supporting them. This arrangement of striking-casting in line with and supported by the draft girders results in shocks received by the former being transmitted directly to the latter, which must ultimately bear them, without putting undue strain on the end sill, and these parts can be made strong enough to take the strain without injury and without adding unnecessary weight. Moreover, in case of collision, the damage to the car from lading in the car shifting and knocking out the end wall is greatly lessened, as the arrangement of end posts and end sill is such as to transfer the brunt of the blow from within directly to the striking-casting without any possibility of tearing loose the end posts or end sill.

It is evident that other forms and shapes of posts, sills, and striking-castings may be used than those illustrated in the accompanying drawings without departing from my novel arrangement, and I do not wish to limit myself to the shapes of parts herein shown, but

What I desire to claim is as follows:

1. In a car end framing, end sills and draft girders, and a striking-casting comprising a bumper having an upwardly extending flange portion adapted to be secured to the sill, and two depending arms offset from the ends of said bumper and arranged at the extremities of the draft girders and rigidly secured thereto, said arms being provided with inside and outside walls connected by web portions terminating at their lower ends in bifurcations, and said striking-casting being formed with pivot bearings spaced laterally from both ends of said bumper above said bifurcations.

2. In a car end framing comprising end sills, end posts and draft girders, a striking-casting having a flange portion rigidly secured to the sill and end posts, two depending arms arranged at either extremity of said striking-casting and provided with web portions rigidly secured to the ends of the draft girders, said arms terminating in bifurcations between which the carry-iron for the draw-bar may be positioned, and an integral connection between said arms and flange portion substantially in line with the end posts.

3. A striking-casting for railway cars comprising a bumper, an upwardly extending flange portion adapted to be secured to the car, two depending hollow arms arranged at each extremity of said bumper, the inner walls of said arms being adapted to be secured to the ends of the draft girders of the car, each of said arms terminating in bifurcations adapted to receive the ends of a draw-bar carry-iron, and the top walls of said arms being recessed to receive and hold in position supports for the ends of said draw-bar carry-iron.

4. In a car end framing comprising draft sills, a metal end sill, and a striking-casting secured thereto, end posts terminating below the top of said end sill and supported on a flange secured thereto, said end posts being secured to said striking-casting and to said flange, and said striking-casting being directly secured to said draft sills, whereby a rigid connection between said parts is secured.

5. In a car end framing comprising a metal end sill, and a striking-casting secured thereto, end posts terminating below the top of said end sill, said end posts being secured to said striking-casting whereby a rigid connection between said parts is secured.

6. In a car end framing, in combination with a striking-casting, an end sill secured to said striking-casting, end posts supported on said end sill, and securing means for said end posts passing through said striking-casting.

7. In a car end framing, in combination with draft girders and a striking casting rigidly secured thereto, an end sill having a vertical web secured to said striking casting, a flanged member having a vertical flange secured to said end sill and a horizontal flange secured to said draft girders, end posts supported on said flanged member, and securing means for said end posts passing through said striking casting.

Signed at St. Louis, Missouri, this 28th day of August 1911.

VINTON E. SISSON.
